(57) **CLAIM**

The ornamental design for a football helmet digital clock, as shown and described.

DESCRIPTION

FIG. 1 is a front perspective view of the football helmet digital clock showing my new design.

FIG. 2 is a front elevational view thereof.

FIG. 3 is a rear side elevational view thereof.

FIG. 4 is a side elevation of the football helmet digital clock as seen from the right side of FIG. 2;

FIG. 5 is a side elevation of the football helmet digital clock as seen from the left side of FIG. 2; and,

FIG. 6 is a top plan view thereof.

The broken lines in the drawings are for illustrative purposes only and do not form part of the claimed design.
